UNITED STATES PATENT OFFICE.

ROBERT CATTLEY JACKSON, OF CALGARY, ALBERTA, CANADA.

PROPELLER.

Application filed July 5, 1921. Serial No. 482,480.

To all whom it may concern:

Be it known that I, ROBERT CATTLEY JACKSON, a subject of the King of Great Britain and Ireland, and a resident of Calgary, in the Province of Alberta, in the Dominion of Canada, have invented certain new and useful Improvements in Propellers, of which the following is a specification.

My invention relates to improvements in propellers the objects of which are to prevent radial dispersion and reduce surface friction by the application of suitable cutting and controlling devices to the blades of the propeller. In order to reduce surface friction the said devices are so designed that the channels formed between them will be in the form of venæ contractæ which formation will induce a differential velocity of flow across the propeller blades.

It is generally accepted that the rotation of a propeller in an unstable medium such as air or water causes a dispersion of the said medium towards the periphery, the amount of such dispersion and friction being a function of the speed of rotation and the pitch of the propeller driving face. The driving efficiency of a propeller being decreased by the dispersion of the medium towards the periphery it would appear to be necessary to control this dispersion by the application of fins, ribs, or vanes, to the driving faces of the propeller and arranged in such manner as to guide the flow of the medium in the required direction.

It would appear to be a simple matter to attach or form fins, ribs, or vanes upon the driving face of the blades of propellers to bring about the desired results, and several attempts have been made with this end in view. It has been found that this can only be successfully accomplished by careful design based upon the application of scientific principles. The surface friction must be reduced by the induction of a differential velocity of flow of the medium and in such manner that the medium shall not receive too positive a grip from the fins, ribs, or vanes which might result in the propeller carrying around with it a quantity of the medium thereby adding to the weight and the frictional resistance of the propeller without increasing its efficiency.

In the accompanying drawings similar characters refer to similar parts throughout the several views.

Fig. 1 is a plan view of the blade of a propeller for use in water.

Fig. 2 is an end view of the same blade showing in broken lines a vane or rib in section.

Fig. 3 is a side view of the same blade.

Fig. 4 is a plan view of the blade of an air propeller.

Fig. 5 is a side view of the same blade.

Fig. 6 shows a series of cross sections through the propeller blade showing fins, ribs or vanes in broken lines.

In the design of propeller blades, for either marine or air propulsion, in addition to all other considerations the pitch or dip plays an important part. At the centre of rotation the circumferential distance travelled is less than at the periphery and consequently if the pitch or dip were equal the whole length of the blade the amount of work done at the periphery would be considerably in excess of that at the centre of rotation. In order to distribute the work done the pitch or dip of the propeller is greatest near its centre and decreases towards the periphery. The effect of this variation not only distributes the work done but tends to diffuse the medium towards the periphery which diffusion I desire to limit and control. The formation of channels such as those illustrated accomplishes this result, the blades (a) having mounted or formed thereon specially shaped fins, ribs, or vanes (b); the fins, ribs, or vanes illustrate a cutting device (c) at the front or driving edge of the propeller blade forming a tapering channel between said fins, ribs, or vanes terminating in a throat (d) and then expanding towards the following edge (e).

In the drawings the central axis of each rib or vane (b) is shown concentric, and their outer edges are shown eccentric, to the centre of rotation, but I do not desire to limit myself to the use of the fins, ribs, or vanes, in the actual position shown thereon. The auxiliary fins, ribs or vanes are to be so arranged relatively to one another as to form venæ contractæ producing, in the flow of the medium through each of them, the well known "Venturi effect" thus causing a differential velocity of flow of the medium across the surface of propeller blades. The differential velocity of flow of the medium obtained in the foregoing manner will bring about considerable reduction

in skin or surface friction, not only on the auxiliary fins, ribs, or vanes but also on the working surface of the propeller. The height and position of these fins, ribs or vanes should be such that the work done will be distributed uniformly over the propeller blades.

What I do claim as my invention, and desire to secure by Letters Patent, is,—

- 10 1. In combination with a propeller of means for cutting, and controlling the flow of, the medium in which it rotates, such means consisting of a plurality of auxiliary fins, ribs or vanes projecting substantially perpendicularly to the driving faces of the propeller blades and so shaped and arranged
- 15

that they will form channels on such driving faces substantially in the form of venæ contractæ.

2. In combination with a propeller of means for inducing a differential velocity of flow of the medium across the faces of the propeller blades which said differential velocity is produced by the medium passing along channels between the specially shaped fins, ribs, or vanes formed or secured upon the propeller blades substantially as described.

ROBERT CATTLEY JACKSON.
